Primary Examiner — Cynthia Ramirez(74) *Attorney, Agent, or Firm* — Stevens & Showalter LLP(57) **CLAIM**

The ornamental design for a manlift overhead guard, as shown and described.

DESCRIPTION

FIG. 1 is a perspective view of a manlift overhead guard as seen from the top, first and right sides;

FIG. 2 is a first side elevational view thereof;

FIG. 3 is a second side elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view of the manlift overhead guard as seen from the bottom, second and right sides.

The broken lines shown in the figures depict portions of the manlift overhead guard which form no part of the claimed design.
